UNITED STATES PATENT OFFICE.

JOSEPH ROBERTS, OF WYANDOTTE, KANSAS.

SWITCH-STAND ATTACHMENT.

SPECIFICATION forming part of Letters Patent No. 363,001, dated May 17, 1887.

Application filed September 23, 1884. Serial No. 143,792. (No model.)

To all whom it may concern:

Be it known that I, JOSEPH ROBERTS, a citizen of the United States, residing at Wyandotte, in the county of Wyandotte and State 5 of Kansas, have invented certain new and useful Improvements in Switch-Stand Attachments, of which the following is a specification, reference being had therein to the accompanying drawings.

10 This invention relates to switch stands, and has for its object a danger signal so combined, constructed, and operating therewith as to present a safety-signal while the main track is complete or continuous, and at the same time 15 being capable of showing a danger-signal continuously while one of several side tracks is thrown into line with the main track, the mechanism employed being such that the restoration of the main track will reverse the 20 signal from "danger" to "safety."

The construction and operation of the invention will be hereinafter described, and the novel features thereof specifically set forth in the claims.

25 Referring to the drawings, Figure 1 is a perspective of the switch-stand and signal; Fig. 2, a central vertical section with the signal in elevation. Figs. 3, 4, and 5 are horizontal sections, showing the signal-operating devices in 30 the several positions which they assume when the main track is complete and when the first siding is in line with the main track, and when the second siding is in line with the track, respectively.

35 Like letters indicate like parts in all the figures.

In any suitable frame-work, as A, there are mounted two vertical shafts, B C, the former provided with a crank or arm, B', adapted to 40 operate any usual connecting-bar, which is secured in any usual manner with the swinging rails of a switch, so that when shaft B is rotated the arm B' rotates with it and throws the swing-rails into line with the communicating 45 rails of the main track and the sidings.

At the top of the frame-work is a substantially circular table, D, through which the shafts B and C project, the former being provided with an arm, B², having pivotally secured thereto an operating-lever, B³. The 50 edge of the table is provided with notches, in

55 this instance three in number, D' D² D³, and the lever B³ is adapted to rest within the notches when in a vertical position, thereby serving to lock the shaft and its arm B' in one of the three positions. The shaft C is provided 60 with a day-signal, E, and with a night-signal or lamp, E', having the usual safety and danger indicators F and G, respectively. Directly beneath the table, and mounted upon the shaft B, is a disk, H, having a single projecting tooth, H', while upon the shaft C is a smaller disk, I, having a single notch, I', adapted to receive the tooth H', and having at each side of the notch concave depressions I² I³, adapted 65 to fit the periphery of the disk H at other points than where the tooth H' occurs.

In this instance the table D is provided with three notches; but, if desired, it may be provided with an additional number of notches, 70 when the same advantages will be secured as with three, as will appear more clearly hereinafter; and I therefore do not limit myself to the adaptation of my invention to switches comprising only two sidings and a main track. 75

The operation of the invention is as follows: Taking the arm B' in a position which would result from dropping the lever B³ into the notch D', said arm would be directly beneath the notch D', as shown in Fig. 3. Let it be 80 understood that when the arm B' is in that position shown in Fig. 3 the main track is complete or continuous and unbroken. Now, by lifting the lever B³ from the notch D' to a horizontal position it falls into the slot B² in 85 the arm B², thereby forming an extension of said arm, giving leverage, so as to render the operation of swinging the rail less laborious than would be the case were the arm B² shorter. When thus raised, the lever is swung one-quarter of a revolution in this instance, and 90 dropped into the notch D², and this operation of the lever and the shaft B and its arm B' brings them to the position shown in Figs. 1, 2, and 4. In the meantime the disk, being 95 fixed upon the shaft B, is also turned a quarter-revolution, during which its tooth H' has been caused to mesh with the notch I' of the disk I, so that the latter disk has also been rotated a quarter of a revolution, thus rotating 100 with it the shaft C, to which it is affixed, and the danger-signals mounted thereon being, as

is customary, at right angles to each other, changes them from "safety" to "danger"—that is, bringing the indicators F, which were at right angles to the main track, parallel to said track, and presenting at right angles to said track the danger-signals G. Now, it will be observed that the concave seat I² of the disk I has been changed in position, for at the start the concave seat I³ had a bearing on the periphery of the disk H, as shown in Fig. 3; but after the movement described of the lever and the arm B' the concave seat I² is brought to bear upon the periphery of said disk H, and at the opposite side of its tooth H'. Now, it will be observed that the lever B³ and arm B² and shaft B, with the disk H, may be rotated for any distance short of that which would bring the tooth H' in contact with the edge of the disk I—that is to say, there may be several notches formed in the periphery of the table D intermediate, though not shown, and each of said additional notches may serve to bind the arm by means of the lever B³, dropped thereinto, and also the arm B' and the swinging rail opposite just as many side rails as there are notches. Hence, as hereinbefore stated, I do not limit myself to the use of my invention to a switch restricted to two sidings and a main track.

It is readily apparent that in moving the lever from the notch D' to D², as just described, the swinging rail is brought into communication with a siding—as, for instance, the first siding at one side of the main-track rail. So, by a similar movement of the lever from notch D² to notch D³, the said swinging rail is brought into communication with a second siding outside of the first, and in such a movement of the lever the disk H is moved from the position shown in Fig. 4 to that position shown in Fig. 5, the disk I remaining motionless in order that, the main track still being broken, the danger-signal shall remain undisturbed. Any movements of the lever between the notches D³ D², so as to throw the main track upon either one of the sidings, does not affect the danger-signal, by reason of the non-opera-

tive position of the disk I relative to the disk H; but so soon as the lever is moved from the notch D³ toward the notch D', then the tooth H' immediately meshes with the notch I' and rotates the signal-shaft to present the safety-indicators at the same time that the arm B' throws the swinging rail in line with the main track.

The lever B³ can be locked in a vertical position within one of the notches D' D² D³ of the stand by inserting a short bar or flat key in a slot, b³, in the upper end of said lever in front of a shoulder, b², projecting upward from the arm B², and a padlock may be attached to said flat key.

Having described my invention and its operation, what I claim is—

1. In a switch-stand, the combination of a signal-shaft and a rail-operating shaft with a toothed disk mounted on the rail-operating shaft and a notched and concave-seat disk mounted on the signal-shaft, substantially as specified.

2. The combination of the shaft B³ provided with the disk H, having the tooth H', with the shaft C, provided with the disk having the notch I' and the concave seats I² I³, substantially as specified.

3. The combination of the shaft B, having the arms B' B², and the disk H, having the tooth H', with the shaft C, carrying the signals, and having the disk I, provided with the notch I' and seats I² I³, and means for locking the arm B² at desired points, substantially as shown and described.

4. The combination of the notched table D, the shafts B and C having the disks H and I, constructed as described, the arm B², mounted upon the shaft B, and provided with a pivoted lever, B³, substantially as shown and described.

In testimony whereof I affix my signature in presence of two witnesses.

JOSEPH ROBERTS.
